RAG DOLL

Dorothy Mae Sanders and Ida V. Avey,
San Marcos, Tex.

Application May 14, 1947, Serial No. 747,896

1 Claim. (Cl. 46—159)

1

This invention relates to improvements in rag dolls.

An object of this invention is to provide a thoroughly flexible, stuffed cloth doll having multi-sectional leg and arm members, said sections forming a portion of and extending over a selected segment of the body portion.

Another object of this invention is to provide improved means for forming the desired bulges in the leg and arm sections, utilizing but a single seam on each side of each leg and arm.

A further object of this invention is to provide improved simulated ears formed by proper folds and seams giving the appearance of a closely approximated human ear.

A still further object of this invention is to provide improved means for retaining eyes, nose and mouth portions within the head section of the doll.

A still further object of this invention is to provide resilient means for urging the leg sections in selected, predetermined directions.

A still further object of this invention is to provide improved simulated feet members having a single toe disconnected from the remainder of the toes in order that walking might be facilitated.

Another object of this invention is to provide improved means for forming simulated hair on the head portion of the doll.

Other objects and features of novelty will become apparent in following the description of the preferred embodiment of the present invention, illustrated in the accompanying drawings, wherein:

Figure 1 is a pictorial view of a preferred embodiment of the present invention, showing the same in a sitting position;

Figure 2 is a pictorial view of the invention shown in Figure 1, showing the same in a walking position;

Figure 3 is a fragmentary elevational view of the leg portion primarily, showing particularly the elastic biasing means for urging the legs in a selected, predetermined direction;

Figure 4 is an elevational view of the eye, nose and mouth retaining means forming part of the present invention;

Figures 5 and 6 are pieces or patterns used in forming the body portion of the invention;

Figures 7 and 8 are leg segments used in forming the legs of the invention; and

Figures 9 and 10 are head pieces forming part of the present invention;

2

Figure 11 is a schematic view showing the application of a selected one of said head pieces; Figures 12 and 13 are hand patterns;

Figures 14 and 15 are portions of the feet of the invention;

Figures 16 and 17 are patterns of the arm elements forming part of the present invention;

Figure 18 is the pattern of the ear portion;

Figure 19 is a pattern of the nose portion; and Figure 20 is a pattern of the seat portion utilized in stuffing the body portion of the doll separately from the leg and arm portions.

Referring now in detail to the illustrated preferred embodiment of the present invention, like reference characters are used throughout to indicate similar elements.

The body portion of the doll is composed of a plurality of pieces which are identified in shape in the drawings. It is noted at this point that the pieces and patterns therefor will be identical in shape, and accordingly the words "pieces" and "patterns" will be used throughout the specification to indicate portions of the casing forming the doll. The front body pattern 10 exemplifies only half of the front portion of the torso, another piece identical to the piece disclosed in Figure 5 to be utilized in conjunction therewith to form the completed external front. The dotted lines 12 and 14, respectively, indicate external seams for receiving the end portions 18 and 20, respectively, of arm members 22 and 24 thereon. These arm members are received on the body portion after the said body portion is fabricated and stuffed.

Taking Figure 6, there is disclosed a back portion of the torso 26 having a dotted seam 28 extending arcuately therethrough. A portion of the edge 18 (Fig. 16) engages the said seam line 28, while the extremities 30 and 32 are matched and joined in forming the body portion. The exterior edges of the patterns disclosed in Figures 5 and 6 are matched and sewed or otherwise joined, thereby forming the body and neck portions of the rag doll. Of course, only one piece or pattern of the front and back are disclosed, the invention requiring a duplication of these elements to form the body.

Viewing Figures 9 to 11, there are disclosed head elements. The said element 36 forms a portion of the neck at 40, while the extremities 42 and 44 form the chin, cheeks and sides of the head of the rag doll. The tab 46 extends down the front of the body portion beneath the two front body members 10. An arcuate extension 48 provided opposite the said tab 46 is utilized in

forming a portion of the mouth of the invention. A similar tab 50 is provided at one extremity of the pattern 38 which cooperates with said arcuate portion 48. The pattern 38 extends over the head portion of the doll forming the forehead, front face and a portion of the cheeks. This portion is generally indicated by the reference numeral 52. The bulge 54 forms the back portion of the head, while the tab 56 extends beneath the patterns of the back 26, being fixedly secured at the bottom thereof.

The extended neck (tabs 46 and 56) is left open until the head is stuffed, then the sides of the tabs are stitched together and the resulting tube is stuffed and the longest tab fastened across the bottom and stitched to keep the stuffing in. The neck is then put through the neck of the unstuffed body torso.

Leg portions 58 and 60, respectively, are provided for forming legs of the invention. It will be noted at this point that the lowermost portion of the body is provided with a seat element 62 for the purpose of stuffing the body after the same has been fabricated. This member 62 is secured to the body portion after stuffing, then is hidden from sight by application of the leg members which will be described at this time.

A single piece 58 is secured to the lowermost rearward portion of the body member forming the back portion of both legs. A dart 64 is provided at the center of said back leg portion 58, thereby imparting both the desired configuration and the desired fit in forming this portion of the invention. It will be noted at this point that the member 58, along with the member 22, is cut on the bias for facilitating bending when the rag doll's arms and legs are moved. The substantially straight edge 66 is secured to the lower front portion of the body member by means of an external seam. The uppermost portion 68 of the said leg piece 60 is secured to the said lowermost portion of the front of the body portion, the edge 68 and a portion of the edge 66 forming a substantially straight line. The marginal portions 70 and 72, respectively, engage appropriate marginal portions of the member 58, thereby forming the legs of the doll.

Simulated feet are provided at the extremity of each leg. Taking Figures 14 and 15, along with Figures 7 and 8, there is seen a dart 74 at the bottom of the said leg elements 58 and a dart 76 extending longitudinally of the pattern of the top portion of the foot 78. The said dart 74 is joined at the lower portion of each leg, while the dart 76 is utilized to encircle the lowermost portion of the entire ankle. The edges 80 meet at the conjunction of the said dart 74, thereby forming a continuation of the seam formed. The bottom portion of the foot 82 is suitably curved to be complementary to the member 78. Simulated toes 84 are sewed together at the terminal portions thereof, and a seam is provided to separate the four smaller toes. It will be noted that the larger toe 86 is disconnected from the remainder of the toes 84, thereby facilitating walking, which operation will be described hereinafter.

The arm members 22 and 24 are joined to the body portion as described hereinbefore, and upper and lower hand portions 88 and 90, respectively are utilized for the purpose of providing the usual simulated hands. The edges 92 and 94 engage the straight edges 96 and 98 of the patterns 22 and 24, respectively, thereby forming a baby-like wrist and hand. Seams are provided for the purpose of defining fingers 100, while a thumb por-

tion 102 extends in disconnected relation therewith. A pleat 104 is provided at the lower hand portion 90 adjacent and through the wrist elements thereof. This pleat simulates the usual hand lines of a child. Further, very small stitches 106 are provided in the upper hand element simulating dimples or knuckles found in an infant's hands.

Referring now to Figure 18, there is disclosed a pattern which is longitudinal having an arcuate end 108 and a slanted opposite end 110. This pattern may be folded, then sewed in the appropriate place to form an extremely realistic ear having the usual creases and channels provided in the human ear. Of course, the ears are sewed in an appropriate place on the head elements.

Taking Figure 19 now, there is a nose pattern 112 which resembles the usual insignia of a gem. It will be noted that the edges 114 are both cut on a bias and are adapted to be folded under the main portion and stuffed, thereby providing a nose element.

Taking now Figures 1 and 2, it will be noted that the hair of the rag doll is composed of satin stitches beginning at the center of the wig, then formed in the usual concentric saddle stitch manner. The extremities of the hair, generally indicated at 120 may be free to curl in bangs, or any suitable hair appearance.

Taking now Figure 4, there is disclosed a means for retaining the eyes, nose and mouth in the selected, predetermined positions. An anchor plate 122 is provided in the head portion of the rag doll and strings 124 extend from said anchor plate to the eyes, nose and mouth. It is noted at this point that this invention contemplates the use of two additional strings for the purpose of providing dimples in the cheeks of the rag doll if so desired. This, however, is purely an optional construction to be dictated by the prerogatives of the manufacturer.

Secured to the seams of the leg elements is a resilient leg biasing means 126 (see Fig. 3) for the purpose of returning the legs to the operative or torso-and-leg alignment position, when moved for walking. By this construction, and resilient means secured to the seams and the lowermost portion of the body member, the doll may be walked on a relatively rough surface, such as a rug. This walking operation per se is known in the art and may be seen in Figure 2.

It is noted in Figure 3 that bulges 128 and 130 are provided in the leg portions. Bulges are also provided (unnumbered) in the arm portions. The method of constructing these bulges is extremely simple, obviating all sewing operations except a single seam on each side of said legs and arms. The first pattern, assume it is the back portion of the leg, is cut at a slight curve, then the upper portion or front of the leg is laid thereon. A dart is cut in the said front portion, while the said front portion is pulled slightly, thereby opening the dart. In this position, the two segments are sewed together and turned inside out. This provides the indentation 132, thereby defining the bulges 128 and 130.

Simulated eyelashes and eyebrows may be provided on the face of the doll and it is the preferable construction to provide insert portions 134 with simulated blue or brown eyes thereon. These inserts may be sewed in place and subsequently held tight by the anchor plate and string construction described hereinabove. It is noted at this point that certain elements of the invention are cut on the bias and others cut on the

straight. This choice of cut permits certain movements such as moving the legs, arms and neck without tending to tear the seams or destroy the material. The upper portions of the hands are also cut on the bias, giving the desired curvature and roundness to the fingers and hand.

While there has been described and illustrated an improved stuffed doll, it is apparent to those skilled in the art that certain alterations may be made therein without departing from the spirit of the invention. Accordingly, limitation is sought only in accordance with the scope of the following claim.

Having thus described the present invention, what is claimed as novel and improved is as follows:

A flexible stuffed cloth doll comprising a casing having a multi-piece body portion, arm and leg pieces for forming part of said body portion, a multi-piece head section having segments of two of said head pieces providing a mouth for said head section, eye and nose members in one of said head pieces, means for retaining said eye and nose members in position, bulges in said leg pieces, resilient means attached to said leg pieces offset from the longitudinal axis of the legs for

urging said leg pieces in aligned position relative to the longitudinal axis of said body portion, simulated hair comprising rows of strands on the head section, said eyes and nose retaining means including a plate in said head section having strings secured thereto connecting said eyes and nose members to said plate, said leg pieces cut on the bias thereby facilitating bending at the joints thereof.
